UNITED STATES PATENT OFFICE.

JAN ZVONÍČEK, OF BRÜNN, AUSTRIA-HUNGARY.

ELASTIC-FLUID TURBINE.

No. 876,422.

Specification of Letters Patent.

Patented Jan. 14, 1908.

Application filed July 5, 1907. Serial No. 382,312.

To all whom it may concern:

Be it known that I, JAN ZVONÍČEK, a subject of the Emperor of Austria-Hungary, residing at Brünn, Moravia, Austria-Hungary, have invented certain new and useful Improvements in Elastic-Fluid Turbines, of which the following is a specification.

My invention relates to turbines which are driven by a vaporous or gaseous agent, and I will now proceed to describe the same with reference to the accompanying drawings.

Figure 1 is a horizontal section through a multiple stage radial turbine combined with an action-wheel. Figs. 2-4 show details of the same. Fig. 5 is a similar view to Fig. 1, drawn to a larger scale and showing a multiple stage turbine without action-wheel. Figs. 6-12 are detail sectional views illustrating the construction and arrangement of the inlet nozzle for the action wheel. Figs. 13-18 are detail views illustrating the construction of the blades for radial flow.

The general construction of the turbine is shown in Fig. 1. On the shaft W there is mounted the running-wheel A, rotating in the chamber K of the turbine casing C. The wheel consists of a disk on one side of which are rings of revolving blades k, while the stationary blades k¹ are secured to the cover B of the casing. With the running-wheel A there is connected an action-wheel A₁, located in a second chamber K₁ of the casing C. The chambers are separated by a partition S. The steam enters through the nozzle (Figs. 6-12) into the chamber K₁ (Fig. 1), flows past the action-wheel A₁, which is provided with one or more rings of blades radially or axially disposed and enters the chamber K. The two chambers communicate either through apertures o in the wheel A or through pipes located outside the casing and the passage H in the center of the chamber K. The exhaust steam escapes to the outlet through an annular passage D.

In cases where the action-wheel is deemed unnecessary, *e. g.* for low steam pressures, the construction shown in Fig. 5 is adopted. The steam here enters through the central inlet H in which an ordinary throttle valve or the like may be fitted.

My purpose is to provide the surfaces at all the joints—in particular, those between the various pressure-stages, between individual relief-spaces, and in the stuffing-box of the

shaft—in such manner that the width of gap 55 at these joints can be diminished to the smallest extent practicable, in such a manner that it is as far as possible uninfluenced by variations of temperature. For this purpose all the said surfaces are disposed in planes at 60 right angles to the axis of rotation, their axial distance being kept as small as possible, and the surfaces moreover so arranged at the stationary and the rotary parts, that on motion of the shaft in longitudinal direction the 65 width of gap either increases or diminishes at all the joints. This part of the invention is illustrated in Figs. 1 and 5. The joints at the various pressure-stages are effected by the surfaces of the blade-rings k, k¹ (Fig. 5) 70 and corresponding surfaces on the casing cover and the running wheel, the width of gap being capable of alteration by axial sliding of the shaft. If the running-wheel A is furnished with action-blades it is sufficient 75 to make a close joint only at x, and according to my invention all the joint-surfaces are disposed exactly or substantially in a plane at right angles to the axis of rotation. In the case of reaction-blades there must also be 80 a close joint made at the parts x¹, which may likewise be disposed in one plane, and the axial distance of these surfaces in front of the surfaces x is the longer the greater the length 85 of the blades, which corresponds to an alteration of the gap-width, on variation of temperature, substantially proportional to the length of the blades, and corresponds consequently also to losses of steam to the same extent per cent.

The relief-spaces at the opposite side of the running-wheel A have close joints at the surfaces y. These surfaces are on the movable rings l secured to the running-wheel, and on the stationary rings m secured to the 95 casing. They are so disposed that the gap-width on axial motion of the shaft alters in the same direction, just as with the joints x, x¹. All the surfaces y may be located in one plane, and their axial distance from the 100 surfaces x depends merely upon the thickness of the disk, so that it may be very small.

The stuffing-box packing is of the well-known so-called "labyrinth" type, with mutually engaging rings, and is so arranged that the joint-surfaces z, z¹ lie in exactly the same plane as the surfaces y.

Naturally all the various joints at x, x^1, y, z, z^1 may be made by means of a number of surfaces engaging in the manner of a labyrinth, as is well known (Fig. 2).

- 5 In order that the gap-width at the joints may not alter on changes of temperature, not only must the axial distance between the various joints be small, but the axial distance of the joints from the thrust bearing in 10 which the shaft is mounted to prevent longitudinal shifting, must be also as small as possible. This has proved very difficult in practice: according to my invention the thrust bearing L_1 (Figs. 1 & 5) is not secured 15 direct to the frame G , but to the extra bearing L_2 . The latter can by means of two keys g_1, g_2 , having a lateral inclined face (Fig. 3) and capable of adjustment by means of screws s_1, s_2 be adjusted in axial direction, even during running of the turbine. By 20 this means for like coefficients of expansion of the bearings $L_1 L_2$ and shaft W the same conditions exist as if the shaft were held in the plane II-II, instead of in the plane I-I. 25 If, however, for the bearing blocks $L_1 L_2$ a suitable material with a greater coefficient of expansion is selected, the injurious influences of expansion of the shaft on the gap-width of the joint-surfaces can be almost entirely 30 overcome. For the purpose of being able still better to attain this latter object, the turbine casing C in which the stationary joint-surfaces are located may be so secured that on axial expansion of the shaft and consequent shifting of the rotary joint-surfaces, 35 the casing shifts by the same amount and in the same direction. Such a manner of securing the casing is shown in Fig. 1. The turbine casing C rests with capability of sliding on bearers F and is connected with the frame G in axial direction by rods M . The rods present inner chambers which communicate with the interior of the turbine casing, so that the temperature of the rods 40 like that of the shaft depends upon the temperature of the steam. The exact place for securing, III-III, can be determined experimentally, in such manner that the expansion of the rods M perfectly compensates for the expansion of the shaft. Instead of hollow rods there may be employed for the same purpose correspondingly formed hollow cast-on pieces communicating with the interior of the turbine. 45 For the purpose of approaching the bearing L_2 to the joint-surfaces and to the center of gravity of the wheel, if possible, in axial direction, the action-wheel A_1 is not mounted direct upon the shaft, but is secured to 50 the wheel A , whereby the casing wall E can be given a conical form, such as is advantageous in point of strength, and sufficient space obtained for the stuffing-box and the bearing.

My invention also relates to the arrangement of the partition S and cylinder cover B , so as to reduce as far as possible the injurious action of unlike temperature, which is highest in the middle of the chamber K and decreases toward the periphery, and the thus caused deformation and strain on the partition and cover. For this purpose:

(a) The running-wheel A is so disposed that the relief-spaces lie on the side facing the partition S . In view of the fact that the steam escaping through the labyrinth y , and thus not doing any work, only slightly alters its temperature, the partition is therefore exposed on both sides to steam of almost the same temperature, so that there is no tendency to bend.

(b) The guide-rings, which corresponding to the temperature of the steam are also of unlike temperature, are not bolted direct to the cover B , but to an intermediate disk B_1 , so that between the latter and the cover there is a free space r which can be filled with the steam of a suitable middle stage. The intermediate disk B_1 itself is so secured that it can expand freely toward the cover. In Fig. 1 the arrangement is such that only the four inner guide-rings are secured to the partition; with great differences of temperature between the center and periphery two or more partitions may be employed instead of only one, the outer guide-rings being then not secured direct to the cover, but to a second or third partition, and the space r can extend nearly to the periphery of the cover. By this means the temperature of the cover is compensated for in radial direction and strain and bending thereof obviated. The intermediate disks B_1 may also be cast in one piece with the cover B in such manner that they are connected to the same only at the periphery (Fig. 4).

My invention relates further to the construction of the inlet-nozzle for the action-wheel A_1 and its arrangement in the turbine chamber K_1 . In Figs. 6 and 7 a nozzle for a wheel with radial flow is shown, while Figs. 8-10 show a nozzle for a wheel with axial flow, with modified construction of the regulator valve, and Figs. 11 and 12 the arrangement of the nozzle for axial and radial flow respectively. The inlet nozzle, Figs. 6-10, consists of a number of compartments and is built up of a plurality of members P and plates R , which are bolted or riveted together. The members P are furnished with passages a of rectangular cross section, which latter are separated from each other by the plates R , the ends constituting nozzles b . All the inside faces of the passages and nozzles may be exactly tooled before being riveted together. The partitions R are inclined at a certain angle of admission to the periphery of the wheel (in radial turbines,

Fig. 6), or to the side of the wheel (in axial turbines, Fig. 8), and may be narrowed at the point of exit, whereby the current of steam will be interrupted. The members 5 P, to render the construction simpler, may be of the same thickness throughout. To enable the various nozzle chambers *a* to be opened in succession, a cylindrical or conical rotary slide N is provided, whose axis lies 10 substantially or precisely at right angles to the partitions R; the latter are provided with cylindrical apertures corresponding exactly with the diameter of the slide. Opening and closing of the various chambers 15 10 substantially or precisely at right angles to the partitions R; the latter are provided with cylindrical apertures corresponding exactly with the diameter of the slide. Opening and closing of the various chambers 15 may be effected either by axial shifting of the slide (Figs. 6 & 7)—the closing-edge *c* of the slide being either inclined or provided with notches *d* in order to insure gradual or continuous action; or closing may be effected 20 by rotation of the slide (Figs. 8-10), for which purpose the slide is provided with apertures, whose closing-edges *i* are inclined or the like. In both cases the slide is thoroughly balanced, in the construction 25 shown in Figs. 6 & 7 by the chambers *a* being carried round the slide, and in the construction shown in Figs. 8-10 by the chambers *a* communicating with the slide casing through two or more symmetrical apertures *f*. 30 The invention relates further to the arrangement of inlet-nozzles in the turbine casing, in such manner as is most advantageous for regular inflow of the steam and for ventilation-resistances. For this purpose 35 the inlet-nozzle is located as near the outlet as possible, but somewhat behind the same regarded in the direction of rotation of the running-wheel, so that the steam leaving the action-wheel must flow round the entire 40 wheel before it arrives at the outlet. In view of the fact that the velocity of the steam on leaving the action-wheel is greater in many cases than the peripheral speed of the latter, the steam may also exert a driving 45 action upon the wheel. If this velocity is smaller than the speed of the running-wheel, the ventilating-losses will, at any rate, be decreased by this arrangement, which losses with any other disposal of the inlet-nozzles, 50 and outlet relatively to each other must be greater on account of irregularities caused by the rotating steam. This arrangement is shown in Fig. 11 for a wheel with axial blades and with two speed stages. The 55 inlet nozzle U is located somewhat behind the outlet T (located in front), so that the steam which leaves the last blades O behind the outlet T must flow round the entire running-wheel. In Fig. 12 this arrangement is shown for a wheel with radial flow 60 and with a ring acted upon twice in succession. In view of the fact that the outlet T is usually located at the lowest part of the turbine chamber, this arrangement has the

further advantage with radial turbines, that any overpressure occurring in the gap between nozzle and running-wheel acts in upward direction (against the action of the weight of the running-wheel) and thus decreases the pressure at the bearing. 65

70

My invention relates finally to the construction of the rings of blades with radial flow, the blades being secured between two rings. These latter serve not only to limit individual spaces, but also to take up the centrifugal forces acting upon the blades. One form of construction of the connection between blades and rings is illustrated in Figs. 13-18. The blades are provided at their two ends with flat pins *c*₁, *c*₂ and set in two rings *m*₁, *m*₂ which may consist of an assemblage of separate segments. These rings are provided on the exterior or interior periphery with suitable recesses *d*, Fig. 14, and are let into dovetail grooves turned in the rings *k*₁, *k*₂. The letting in can be done in various ways. 75

80

In Fig. 13 the edges *v*₁, *v*₂ of the rings *k*₁, *k*₂ after insertion of the rings *m*₁, *m*₂ and blades are somewhat bent in. The edge *v*₂ is drawn in the unbent position, as it comes from the lathe, while the edge *v*₁ is shown in the bent position. 90

95

In Fig. 16 a method of connection is shown with which the rings *m*₁, *m*₂ are secured in the dovetail grooves of the rings *k*₁, *k*₂ with the aid of wedge shaped elevations *f*₁, *f*₂. In this case also the ring *m*₂ is shown as it leaves the lathe, while the ring *m*₁ is drawn in position, forced into the groove. 100

105

Fig. 17 illustrates a method of connection with which the rings *m*₁, *m*₂ are pressed in by bending them into the dovetail grooves of the rings *k*₁, *k*₂, this being done by pressing together the two rings *k*₁, *k*₂. The ring *m*₂ is shown in the position prior to being pressed into the groove, while the ring *m*₁ is shown in the pressed in position. 110

105

In Fig. 18 the rings *m*₁, *m*₂ are held in the dovetail grooves of the rings *k*₁, *k*₂ by the gaps *p*₁, *p*₂ being filled up with solder or like means after the two parts have been assembled. 115

The end-pins *c*₁, *c*₂ of the blades may be thicker at their ends than at the root, for the purpose of effecting a better connection. The dovetail groove in the rings *k*₁, *k*₂ may have a conical shape not only on the interior but also on the exterior periphery (*h*₁, *h*₂, Fig. 18), in which case it is desirable in inserting the rings *m*₁, *m*₂ in the rings *k*₁, *k*₂, to heat the latter. 120

The end pins *c*₁, *c*₂ of the blades may be made thicker in radial direction than the depth of the recesses *d* in the rings *m*₁, *m*₂, so that these pins after being set in place project somewhat from the periphery of the rings *m*₁, *m*₂. In this manner the pins are 125

firmly pressed together at both sides whereby loosening is rendered impossible.

Having thus described my invention, what I claim as new and desire to secure by Letters Patent is—

1. In an elastic fluid multiple stage turbine, a casing, a shaft, a stuffing-box therefore, a running wheel, an active wheel, a partition between said wheels, and relief spaces between said partition and running wheel, the joint surfaces between said wheels, in the relief spaces, and in the stuffing box, lying in planes at right angles to the axis, the width of the spaces being regulated simultaneously upon the axial sliding of the shaft due to expansion and contraction, substantially as described.
2. In an elastic fluid multiple stage turbine, a casing, a shaft, a stuffing-box therefore, a running wheel having laterally projecting blades, rings of stationary blades on the casing alternating with the wheel blades, an action wheel, a partition between said running and action wheels, and relief spaces between said partition and running wheel, the joint surfaces between said wheels, in the relief spaces, and in the stuffing box, lying in planes at right angles to the axis, the width of the spaces being regulated simultaneously upon the axial sliding of the shaft due to expansion and contraction, substantially as described.
3. In an elastic fluid multiple stage radial turbine, a framing, a shaft, a running-wheel, an end-bearing located adjacent to the latter and adjustably secured in the framing, and a thrust bearing for the shaft, secured to first said bearing, whereby expansion of the shaft can be compensated for, substantially as described.
4. In an elastic fluid multiple stage radial turbine, a framing, and a casing secured thereto by hollow members heated by the steam in the casing, whereby expansion of the shaft is compensated for, substantially as described.
5. In an elastic fluid multiple stage radial turbine, a wheel, a shaft having a thrust bearing, and an action-wheel secured to the wheel instead of direct to the shaft, whereby the shaft bearing can be located closely adjacent to the turbine wheel, substantially as described.
6. In an elastic fluid multiple stage radial turbine, a casing having a partition and a running wheel and action wheel on opposite

sides of the partition, the relief-spaces of the wheels being on their sides next the partition, whereby the latter is exposed on both sides to steam at the same temperature, substantially as described.

7. In an elastic fluid multiple stage radial turbine, a guide-wheel, a cylinder having a cover and presenting partitions to which the guide-wheel rings are secured, a space being presented between partitions and cover, which can be heated by steam of a middle stage, substantially as described.

8. In an elastic fluid multiple stage radial turbine, an inlet device, comprising a casing, a plurality of flat members hollowed to present nozzles, plates separating said members, and a balanced regulator slide working in the casing, its axis being substantially at right angles to said plates, whereby on actuation of the slide the nozzles are opened or closed in succession, substantially as described.

9. In an elastic fluid multiple stage radial turbine, blades presenting projections, rings recessed to receive the latter, and blade-rings presenting lateral dovetail grooves into which said rings fit, substantially as described.

10. In an elastic fluid multiple stage radial turbine, blade rings presenting lateral dovetail grooves, blades presenting projections, and rings upon which said projections are engaged, said rings and blades being engaged in the dovetail grooves of the blade rings, substantially as described.

11. In an elastic fluid multiple stage radial turbine blades presenting projections, rings recessed in their outer peripheries to receive said projections, and blade rings presenting lateral dovetail grooves into which said rings fit, substantially as described.

12. In an elastic fluid multiple stage radial turbine blades presenting projections, rings recessed in their outer peripheries to receive said projections, and blade rings presenting lateral dovetail grooves into which said rings fit, the rings and blade rings being provided on adjacent surfaces respectively with wedge-shaped recesses and, corresponding projections, substantially as described.

In testimony whereof I affix my signature in presence of two witnesses.

JAN ZVONÍČEK.
